CONTROL SYSTEM

Richard B. Hunter, Shorewood, Wis., assignor to
Cutler-Hammer, Inc., Milwaukee, Wis., a cor-
poration of Delaware

Application June 22, 1938, Serial No. 215,164

9 Claims. (Cl. 175—312)

This invention relates to control systems and more particularly to regulating systems.

More specifically the invention relates to voltage regulating systems, and although not limited in its application the invention is of particular advantage in connection with theater light dimming systems. In such a system it is desirable, especially in connection with the presetting of intensities of illumination for different scenes, that the intensity of illumination of a lamp circuit shall accurately correspond to the indication of a control device employed to vary the illumination.

However, in systems of the aforementioned character which employ series connected impedances, such as variable resistances and reactances, the voltage drop across the series impedance device changes with changes in the load, and consequently the position of the indicator is not always an accurate indication of the degree of illumination.

In prior systems this difficulty was partially overcome by utilizing saturable reactors of special design and construction, which due to their special design were expensive. Various other devices and arrangements have heretofore been proposed to overcome the aforementioned undesirable characteristics of series impedances, such, for instance, as the regulating system disclosed in my Patent No. 1,931,799, dated October 24, 1933, which operates satisfactorily within the limits and for the purposes for which it is designed, but which is somewhat complicated when operated in connection with a theater lighting system having a plurality of lamp circuits. Other regulating systems have been proposed wherein the voltage supplied to a lamp circuit of variable load is controlled by means responsive to a control voltage and a second voltage derived from the controlled circuit, such systems employing electric valve and other apparatus involving relatively high original cost and maintenance expense. Moreover, the aforesaid systems are, more or less, arrangements which compensate for certain undesirable characteristics of series impedances.

Accordingly it is an object of this invention to provide a novel control system which overcomes the aforementioned difficulties and disadvantages.

Another and more specific object is to provide an improved and simplified illumination control system having means for adjusting and maintaining the voltage of a lamp circuit, within a wide range of lamp load, at any desired value corresponding relatively accurately to the indication of a control device.

Another object is to provide an improved illumination control system of the aforementioned character which affords a desired characteristic of variation of the voltage supplied to a lamp circuit.

Another object is to provide control means for a system of the aforementioned character which is simple, efficient and relatively inexpensive.

Another object is to provide a control system of the aforementioned character having extreme flexibility in respect of affording various desired features of manual and/or automatic control.

Other objects and advantages of the invention will hereinafter appear.

15 In practicing the invention in one form thereof I prefer to employ a variable autotransformer dimmer to control the voltage of and degree of illumination afforded by a lamp circuit; or alternatively to control an operating condition of 20 another or similar form of alternating current circuit. The autotransformer dimmer is controlled responsively to a control voltage provided by a suitable control device. The control device is preferably of a type which is adapted to afford 25 indication of the desired operating condition of the circuit, such as a variable resistance, preferably of the potentiometer type, or a variable autotransformer. In a theater dimming system a plurality of such control devices would ordinarily be employed for each lamp circuit, and the same would be arranged to provide for presetting 30 of a corresponding number of intensities of illumination for the lamps of such circuit for different scenes.

35 It is to be understood that while I prefer to employ a variable autotransformer dimmer to control the lamp circuit, other devices having an across-the-line or potentiometer connection may be employed. However, as is well known, the 40 autotransformer has certain inherent advantages, in respect of enabling stable voltage control of a translating circuit, with a high degree of efficiency, at any desired value substantially independently of the value of or changes in the 45 load.

Thus it will be apparent that the variable autotransformer dimmer with its inherent properties for affording the desired character of control of a lamp circuit possesses a very material advantage over series impedance devices.

It is known that variable autotransformer dimmers have been employed heretofore for controlling the voltage supplied to a lamp circuit. It is a further object of this invention, however, to use 66 a variable autotransformer dimmer in a novel

manner in an illumination control system, where-
in the autotransformer dimmer is controlled au-
tomatically in response to a varying voltage sup-
plied by an indicating control device to adjust
and maintain the voltage and degree of illumina-
tion of a lamp circuit, within a wide range of lamp
load, at any desired value corresponding relatively
accurately to the value indicated by said con-
trol device.

The accompanying drawing illustrates an em-
bodiment of the invention in one form thereof in
a theater dimming system for controlling the
intensity of illumination of a lamp circuit, it
being understood that the invention is susceptible
of embodiment in other forms without depart-
ing from the spirit of the invention or the scope
thereof as defined by the appended claims.

In the drawing,

Figure 1 illustrates schematically and diagram-
matically an elementary form of illumination
control system embodying my invention;

Fig. 2 is a similar view of a more complete
form of illumination control system embodying
my invention; and

Fig. 3 is a diagram showing by means of curves
the typical character of control of the voltage
supplied to the lamps which is obtained with the
systems illustrated in Figs. 1 and 2 and the re-
sultant variation of the intensity of illumination
of the lamps.

As is well known, the variable autotransformer
affords substantially linear variation of the volt-
age supplied to the controlled circuit. This has
been found to be a definite advantage in the con-
trol of lamp circuits, since the curve of illumina-
tion intensity variation of the lamps resulting
from linear variation of the voltage supplied
thereto closely approximates the optimum curve
of variation of illumination intensity as enunci-
ated by what is variously known as "Fechner's
law" or "Weber's law." This law states generally
that the sensational effect does not increase pro-
portionally to the stimulus, but as the logarithm
of the stimulus. Thus supposing the stimulus to
be 10, 100 or 1000 times increased, the sensational
effect will not be 10, 100 or 1000 times, but only
1, 2 and 3 times greater. The curve CP of the
diagram, Fig. 3, represents the variation of il-
lumination intensity of the lamps in candle-
power from black-out to full-bright when the
lamp voltage, represented by curve LV, is varied
linearly, or substantially so, from substantially
zero to maximum. It will be apparent that the
curve CP closely approximates the desired curve
aforementioned.

In order to facilitate the description and un-
derstanding of certain features of the invention,
an elementary form of illumination control sys-
tem is shown in Fig. 1. Referring thereto, the
numeral 1 designates a group of electric lamps
which are adapted to be supplied from a suitable
source, such as the source of alternating current
represented by the lines L¹, L². The voltage sup-
plied to the lamps, and consequently the degree
of illumination of the latter, is controlled by
means of a potentiometer impedance device,
shown as the variable autotransformer dimmer
2 which is connected across lines L¹, L². A move-
able contact arm 2^a, connected with lamps 1, is
associated with autotransformer dimmer 2 and
said arm is adapted to be adjusted automatically
in response to unbalance of a balancing control
circuit. The latter comprises one or more vari-
able sending potentiometer impedances 3, 4, a
variable receiving potentiometer impedance 5,

and a balanced relay 6. The impedances 3, 4, 5
are shown as autotransformers and each has as-
sociated therewith a movable contact arm 3^a,
4^a, 5^a, respectively.

5 The contact arms 2^a and 5^a are mechanically
connected with and electrically insulated from
each other and are thus adapted to be moved
simultaneously by the motor M through the
medium of suitable reduction gearing 7. Motor
10 M is a split field motor having directional field
windings F and F' which are adapted to be
selectively energized through the medium of the
stationary contacts 6^b or 6^c and the armature
contactor 6^a of relay 6.

15 Relay 6 is of the two coil type and its contactor
6^a is normally in the neutral position shown, but
when there is a difference between the voltages
across the two coils 6^d, 6^e the contactor is at-
tracted in one direction or the other to energize
20 motor M through one of its fields. Motor M
thereupon operates in the proper direction to
move contact arm 5^a to restore balance of the
voltages across the coils 6^d, 6^e and simultaneously
to move contact arm 2^a to change the intensity
25 of illumination of lamps 1. Unbalancing of relay
6 is normally effected by operation of means for
rendering the sending impedances 3, 4 effective
selectively, said means being shown as a double
throw switch 8. Meanwhile the contact arm of
30 the inactive sending impedance may be moved to
preset another scene. It will be further apparent
that relay 6 may be unbalanced by moving the
contact arm of the active sending impedance.

Further details of the operation of the system
35 shown in Fig. 1 will be better understood from
the following description. Thus the control cir-
cuit is shown as being in a state of balance at a
point to provide for supply of maximum voltage
to the lamps 1 and consequent maximum brill-
iancy thereof. That is, contact arm 3^a is at a
40 point adjacent to line L¹ with respect to sending
impedance 3 and switch 8 is in the position to
render arm 3^a effective. Contact arm 5^a has been
moved to a position with respect to receiving
45 impedance 5 corresponding with that of arm 3^a
by motor M in response to operation of relay 6.
Contact arm 2^a consequently is in a position with
respect to autotransformer dimmer 2 correspond-
ing with that of arm 3^a and thus the lamps 1
50 are connected directly across lines L¹, L² to pro-
vide for maximum brilliancy thereof.

Upon movement of switch 8 to its dotted line
position contact arm 4^a of sending impedance
4 will be rendered effective. Contact arm 4^a is
55 in a position midway between the extremities of
sending impedance 4, indicating ultimate ener-
gization of lamps 1 at fifty per cent of full volt-
age. When contact arm 4^a is rendered active
there will be a difference in the voltages across
60 coils 6^d, 6^e of relay 6 due to the difference in the
positions of contact arms 4^a and 5^a, and con-
tactor 6^a of said relay will consequently be at-
tracted in a direction to engage stationary contact
6^b pending movement of contact arm 5^a to effect
65 balancing of the voltages across the coils. Con-
tact arms 5^a and 2^a will be moved by motor M
in a downward direction, and the control circuit
will be balanced when arm 5^a reaches a position
70 with respect to receiving impedance 5 which cor-
responds with that occupied by contact arm 4^a
with respect to sending impedance 4. Motor M
will then be de-energized by reason of contactor
6^a assuming its neutral position. Contact arm 2^a
75 will then be in a position with respect to auto-
transformer dimmer 2 to impress fifty per cent

voltage on the lamps 1 pending movement of arm 4^a or movement of switch 8 to render arm 3^a effective.

It will be apparent that by employing a variable autotransformer dimmer for controlling the voltage supplied to the lamps 1 insure that a given position of its associated contact arm affords a predetermined value of voltage of the lamps substantially irrespective of the value of or changes in the lamp load, and therefore the lamp voltage will be substantially in accordance with that indicated by the contact arm of a sending impedance. Thus by employing relatively simple means I have found it possible in a preset or indicating illumination control system to obtain accurate voltage control of a lamp circuit in accordance with indicated values substantially irrespective of the value of the lamp load.

Fig. 2 illustrates a more complete form of illumination control system, and is presented to disclose more clearly the manner in which the invention is ordinarily employed. The system of Fig. 2 is essentially like that of Fig. 1, differing mainly therefrom in the provision of refinements and additions to the control means to afford the desired flexibility of control and operation of the autotransformer dimmers.

Two groups of lamps 10, 11 are shown by way of example, and it may be assumed that the lamps of the two groups are of the same color, one group representing stage footlights, for instance, and the other group representing border lights. It is to be understood that additional groups of lamps of the aforementioned and different colors would ordinarily be employed to provide a complete theater or stage lighting system, and that the control means for such additional groups would be arranged in any suitable manner to provide for joint or selective control of all or certain of said groups of lamps.

The voltage supplied to the groups of lamps 10, 11 is controlled by the variable autotransformer dimmers 12, 13, respectively. The latter are connected across lines L¹, L², which represent a suitable alternating current source. Associated with autotransformer dimmers 12, 13 are the movable contact arms 12^a, 13^a, respectively; arm 12^a being connected to lamps 10 and arm 13^a being connected to lamps 11.

Referring to the control means for autotransformer dimmer 12, contact arm 12^a is adapted to be adjusted responsively to unbalance of a balancing control circuit by a reversible split field motor M¹ through the medium of suitable reduction gearing 14. The balancing control circuit comprises the sending autotransformers 15, 16, 17, a receiving autotransformer 18 and a balanced relay 19. Each of the sending autotransformers 15, 16, 17 has associated therewith a movable contact arm 15^a, 16^a, 17^a, respectively. Said contact arms are adapted to be connected selectively to one end or the other of a fader autotransformer 20 through the medium of pairs of manually operable switches 15^b, 15^c, 16^b, 16^c and 17^b, 17^c, respectively. A movable contact arm 20^a is associated with fader autotransformer 20 and is connected to one of the coils of relay 19, the other coil thereof being connected to the movable contact arm 18^a associated with receiving autotransformer 18. Contact arm 18^a is mechanically connected with and electrically insulated from contact arm 12^a of autotransformer dimmer 12 in the manner hereinbefore described.

The fader autotransformer 20 serves in a measure the same purpose as switch 8 in the system of

Fig. 1, except that a more gradual transition of the intensity of illumination of lamps 10 is effected between the values selected by the contact arms 15^a, 16^a, 17^a by moving contact arm 20^a; or, if desired, the degree of illumination of said lamps may be maintained at any intermediate value by adjusting contact arm 20^a to points intermediate the ends of fader autotransformer 20.

The sending autotransformers 15, 16, 17 are supplied with current at a suitably reduced voltage from the secondary winding 30^b of a transformer 30 through the medium of one or both of the scene master autotransformer 28 and the grand master autotransformer 29. The primary winding 30^a of transformer 30 is connected across lines L¹, L². The sending autotransformers 15, 16, 17 are connected at one end to one or the other of contact arms 28^a, 29^a, associated respectively with master autotransformers 28, 29, through the medium of double throw switches 15^d, 16^d, 17^d, respectively. Contact arms 28^a, 29^a are shown in positions with respect to their associated autotransformers to provide for connection of the sending autotransformers 15, 16, 17 directly across the terminals of the secondary winding 30^b of transformer 30. The scene master autotransformer 28 is adapted to be connected directly across the terminals of the secondary winding 30^b or through the contact arm 29^a, selectively, by means of a double throw switch 31. The grand master autotransformer 29 and also the receiving autotransformer 18 are adapted to be connected across the terminals of said secondary winding. Thus by means of the master autotransformers 28, 29 proportional and cascaded potentiometer control of the balancing control circuits for the several groups of lamps in a lighting system may be effected, either jointly or severally. A push button switch 9 is preferably provided to open and close the circuit from the secondary winding of transformer 30 to the balancing control circuit; i. e., the master, sending, fader and receiving autotransformers, and the balanced relay.

The system further includes a line switch 21, continuity switches 22, 23, a normally closed switch 41, and an electromagnetically operated switch 25, the contacts of which are closed upon energization of its winding to connect autotransformer dimmer 12 across lines L¹, L². The winding of switch 25 is energized upon closure of the aforementioned switches 21, 22, 23 and 41. Continuity switch 22 is shown as a double throw color master switch which is ordinarily provided with an additional stationary contact, as shown, which may be connected to a grand master switch in a well known manner to provide for joint continuity control of all or certain of the differently colored groups of lamps employed in a complete theater lighting system. Switch 41 is adapted to be opened as by contact arm 12^a, as shown, when the latter is in its extreme dim position. Thus the winding of switch 25 is deenergized when lamps 10 are black-out, the contacts of said switch being opened to deenergize the lamps 10 and autotransformer dimmer 12.

The operation of the control system, as hereinbefore described, is as follows:

Upon closure of line switch 21 and push button switch 9 the sending autotransformers 15, 16, 17 are connected in parallel across the terminals of secondary winding 30^b of transformer 30, the circuit therefor extending from the left hand terminal of winding 30^b through push button switch 9, by conductors 42 and 43 through

the right hand contact and the contact arm of switch 31, by contact arm 28^a and conductor 44 through the left hand contacts and the contact arms of switches 15^b, 16^c, 17^d, through the autotransformers 15, 16, 17, and by conductor 46 and line L² to the right hand terminal of secondary winding 30^b. With the arrangement shown and just described the illustrated positions of contact arms 15^a, 16^a, 17^a will provide for supply to lamps 10 of zero, fifty per cent and maximum voltages, respectively. Thus assuming closure of switch 15^b (another of the switches, say 17^c, having previously been closed), it will be apparent from the positions of fader contact arm 20^a, the contactor of relay 19 and the receiver contact arm 18^a that the control circuit is balanced at a point to provide for zero voltage and consequent black-out of lamps 10. Dimmer contact arm 12^a, being movable simultaneously with receiver arm 18^a, as aforescribed, is in the extreme dim position, as shown, and is in engagement with an extension on switch 41 to open the same, for the purpose hereinbefore mentioned.

To vary the voltage of lamps 10 from that indicated by sender arm 15^a (zero) to that indicated by sender arm 16^a (fifty per cent) the aforementioned switch 17^c is then opened and switch 16^c is closed to connect arm 16^a to the upper end of fader autotransformer 20, switch 15^b having been closed previously, as mentioned. Fader arm 20^a is then moved to its upper extreme position to provide a predetermined voltage differential across the opposed coils of relay 19. The resultant response of relay 19 effects operation of motor M¹ in a direction to move receiver arm 18^a and dimmer arm 12^a simultaneously to balance the control circuit and to supply fifty per cent voltage to the lamps, respectively. It is assumed that the continuity switches 22, 23 are closed. It is apparent that switch 41 will be closed immediately upon movement of dimmer arm 12^a from its extreme dim position.

In a similar manner, to vary the voltage of lamps 10 from fifty per cent to that indicated by sender arm 17^a (maximum) switch 15^b is opened and switch 17^b is closed to connect arm 17^a to the lower end of fader autotransformer 20. Movement of fader arm 20^a to its lower extreme position will effect response of relay 19, as aforescribed, whereupon motor M¹ will operate in a direction to move receiver arm 18^a and dimmer arm 12^a simultaneously to balance the control circuit and to supply maximum voltage to the lamps, respectively.

It will be apparent from the foregoing that operation of the proper switches (15^b, 15^c, 16^b, 16^c, 17^b, 17^c) and movement of fader arm 20^a alternately to its opposite extreme positions will provide for variation of the lamp voltage and consequently the illumination intensity from one to other of the values indicated by the sender arms 15^a, 16^a, 17^a.

The fields F and F¹ of motor M¹ are adapted to be energized through the medium of the electromagnetically operable switches 32, 33, respectively, the closing windings of said switches being adapted for energization, selectively, by balanced relay 19.

A small normally engaged, electromagnetically releasable brake B is preferably provided to effect stopping of the motor M¹ immediately upon de-energization of the same to avoid hunting by the balanced relay 19. The releasing winding of brake B is connected in series with said motor.

The control means for the group of lamps 11

is similar to that aforescribed. Thus dimmer arm 13^a associated with autotransformer dimmer 13 is adapted to be adjusted by a reversible split field motor M² through the medium of suitable reduction gearing 34 in response to unbalance of a balancing control circuit which comprises the sending autotransformers 35, 36, 37, a receiving autotransformer 38, a balanced relay 39, and a fader autotransformer 40. Each of said sending autotransformers 35, 36, 37 has associated therewith a movable contact arm 35^a, 36^a, 37^a, respectively. Said sender arms are adapted to be connected selectively to one end or the other of the fader autotransformer 40 through the medium of pairs of manually operable switches 35^b, 35^c, 36^b, 36^c, 37^b, 37^c, respectively. Said switches are preferably mechanically connected, for joint operation thereof, with the corresponding switches associated with sender arms 15^a, 16^a, 17^a. Thus switches 15^b and 35^b, 15^c and 35^c, etc., are mechanically connected. By this arrangement the illumination of a plurality of groups of lamps may be varied from one preset intensity to another by manipulation of a minimum number of control devices. Also the contact arm 40^a associated with fader autotransformer 40 is mechanically connected with contact arm 20^a, an arrangement whereby the transition from one to another of the intensities preset for the individual groups of lamps in a lighting system may be effected jointly.

The sending autotransformers 35, 36, 37 are adapted to be connected across the terminals of secondary winding 30^b of transformer 30 through the medium of double throw switches 35^d, 36^d, 37^d, respectively, and through the master autotransformers 28, 29 in a manner similar to that hitherto described.

Proportional dimming of the several groups of lamps may be effected by moving contact arm 28^a of the scene master autotransformer 28 to the position shown in dotted lines, for instance. Cascading control of the several groups of lamps is effected through the medium of the grand master autotransformer 29 by moving contact arm 29^a to the position shown in dotted lines, for instance. Switch 31 would be moved to its dotted line position to obtain such cascaded control.

The continuity of circuit of lamps 11 is controlled by a normally open electromagnetically operable switch 45, the operating winding of which is controlled by switches 22 and 24.

The winding of autotransformer dimmer 13 is shown as provided with additional turns which are connected between the lamps 11 and line L². As is well understood, a voltage will be induced in such additional turns which is proportional as the number of additional turns is proportional to the number of turns connected across the line, and such induced voltage supplements the voltage supplied through the autotransformer proper and is used to compensate for the voltage drop in the line to insure full brilliancy of the lamps when contactor 13^a is in the extreme position opposite to that illustrated.

While I prefer to employ variable autotransformers for the sending, receiving, fader and master potentiometer impedances, as shown, it is to be understood that other kinds of impedances may be employed, such as potentiometer resistors.

It will be apparent from the foregoing that by utilizing a variable autotransformer which is controlled responsively to the setting of an in-

dicating control device the voltage and degree of illumination of a group of lamps will relatively accurately correspond with the value indicated by such device substantially irrespective of changes in the lamp load. The desired character of illumination control is thus provided with relatively simple and economical apparatus. Furthermore the improved regulating system hereinbefore described obviates the necessity for a direct current supply or for rectifiers and provides conveniently and efficiently operable means for obtaining maximum flexibility of control.

What I claim as new and desire to secure by Letters Patent is as follows:

1. In an illumination control system, in combination, a group of electric lamps, a constant voltage source of current supply therefor, means for varying the voltage of said lamps and for maintaining the voltage thereof substantially constant at a desired value, said means comprising a variable potentiometer type impedance device connected across said source and adapted to impress a variable voltage upon said group of lamps, means for regulating the output voltage of said device comprising a plurality of sending impedances each having a contact arm associated therewith and adapted for adjustment to provide for preselection of a value of control voltage, means associated with said sending impedances to provide a balancing control circuit, said last mentioned means including a variable receiving impedance, a fader impedance, means associated with said sending impedance contact arms for connecting any one of the same to either end of said fader impedance and for connecting any other of said contact arms to the other end of said fader impedance, a manually operable contact arm associated with said fader impedance for traversing the same, whereby the control voltage is varied from the value preselected by one of said active sending impedance contact arms to the value preselected by the other of said active contact arms, means including a reversible electric motor operable automatically in response to variation of the control voltage to adjust said receiving impedance, whereby said control circuit is balanced, and simultaneously to adjust the output voltage of said device directly in accordance with and to a degree definitely corresponding to the value of said control voltage, whereby the voltage of said group of lamps is adjusted to and maintained at a value having a predetermined relationship to the control voltage value.

2. In an illumination control system, in combination, a group of electric lamps, a source of alternating current supply therefor, a variable autotransformer dimming device connected across said source for controlling the voltage of said lamps, regulating means for said dimming device comprising a plurality of sending impedances connected across said source, each of said impedances having an associated movable contact arm to provide for preselection of a value of control voltage, a fader impedance, means associated with said contact arms to provide for connection of any one of the same to either end of said fader impedance and to provide for connection of any other of said contact arms to the other end of said fader impedance, a manually operable contact arm associated with said fader impedance for traversing the same, whereby the control voltage is varied gradually from the value preselected by one of said active sending impedance contact arms to the value preselected

5 by the other of said active contact arms, means associated with said sending impedances and said fader impedance to provide a balancing control circuit, said last mentioned means including a variable receiving impedance and means including power operated means operable upon unbalancing of said control circuit due to variation of the control voltage to adjust said receiving impedance, whereby said control circuit is balanced, and simultaneously to adjust said dimming device, whereby the voltage of said lamps is adjusted to and maintained at a value having a predetermined relationship to the control voltage value, and means including an electromagnetically operable brake releasable automatically upon balancing of said circuit to insure stopping of said motor.

10 3. In an illumination control system, in combination, a plurality of groups of electric lamps, a constant voltage source of alternating current supply therefor, a variable autotransformer dimmer for each of said groups of lamps, means for regulating the output voltage of each of said dimmers comprising a plurality of sending potentiometer impedances connected to a suitable source of current supply, each of said impedances having a movable contact arm to provide for preselection of a value of control voltage, a fader impedance, means including switches 15 associated with each of said contact arms, respectively, said switches being operable selectively to provide for connecting any one of said contact arms to either end of said fader impedance and to provide for connecting any other of said contact arms to the other end of said fader impedance, means to provide for joint operation of certain of the switches associated with the respective sets of contact arms, a movable contact arm associated with each of said fader impedances, whereby the control voltage is varied gradually from the value preselected by one of said active sending impedance contact arms to the value preselected by the other of said active contact arms, means to provide for joint operation of 20 said fader contact arms, whereby to effect variation jointly of the control voltages to be provided by said regulating means individually, said regulating means further comprising means to provide a balancing control circuit, said last mentioned means including a variable receiving impedance, and means operable upon unbalance of said control circuit due to variation of the control voltage to adjust said receiving impedance, whereby to balance said control circuit, and simultaneously to adjust the output voltage 25 of said dimmer, whereby the voltage of the group of lamps controlled thereby is adjusted to and maintained at a value having a predetermined definite relationship to the value of control voltage.

30 4. In an illumination control system, in combination, a lamp circuit, a constant voltage source of alternating current supply therefor, means to control the degree of energization of said lamp circuit, said means comprising a variable autotransformer dimming device connected across said source, means for regulating the output voltage of said device comprising a plurality of variable autotransformers connected in parallel 35 across said source and each adapted to provide for preselection of a value of control voltage, means for rendering said autotransformers effective selectively, and means responsive automatically to said control voltage including means operable to adjust the output voltage of said 40

device directly in accordance with and to a degree definitely corresponding to the value of said control voltage, whereby the degree of energization of said lamp circuit is adjusted to and maintained at a given constant value for a given pre-selected control voltage.

5. In an illumination control system, in combination, a plurality of independently controllable lamp circuits, a constant voltage source of alternating current supply therefor, a variable autotransformer dimmer associated with each of said lamp circuits for controlling the degree of energization thereof, means for regulating the output voltages of said dimmers comprising individual variable sending autotransformers to be energized from said source, associated means providing for individual, group and master control of the electrical conditions of said sending autotransformers, said means comprising variable autotransformers so disposed and connected as to provide for maintaining a predetermined definite relation between the electrical conditions of the several sending autotransformers during joint control of such conditions of the latter, and means associated with each of said regulating means and responsive automatically to variations of the control voltages provided by the latter including means operable to adjust the output voltages of said dimmers directly in accordance with and to degrees definitely corresponding to the values of said control voltages, whereby the degree of energization of each of said lamp circuits is adjusted to and maintained at a given constant value for a given value of control voltage.

6. In an illumination control system, in combination, a group of electric lamps, a constant voltage source of alternating current supply therefor, means interposed between said source and said lamps to control the degree of energization of the latter between values providing for substantially zero and maximum intensities of illumination thereof, said means comprising a variable autotransformer dimmer connected across said source, means for regulating the output voltage of said dimmer comprising means for supplying a variable control voltage, means responsive automatically to said control voltage including means operable to adjust the output voltage of said dimmer directly in accordance with and to a degree definitely corresponding to the value of said control voltage, whereby the voltage supplied to said lamps is adjusted to and maintained at a given constant value for a given pre-selected control voltage, and switch means associated with said dimmer and operable automatically upon adjustment of said dimmer to provide for zero intensity of illumination of said lamps to effect complete deenergization of the latter.

7. In an illumination control system, in combination, a group of electric lamps, a source of alternating current supply therefor, means interposed between said source and said lamps to control the degree of energization of the latter between values providing for substantially zero and maximum intensities of illumination thereof, said means comprising a variable autotransformer dimmer connected across said source, regulating means for said dimmer comprising means for supplying a variable control voltage, means responsive automatically to said control voltage including means operable to adjust said dimmer directly in accordance with the value of said control voltage, whereby the voltage supplied

to said lamps is adjusted to and maintained at a given constant value for a given preselected control voltage, and means associated with said dimmer to compensate for voltage drop between said source and said lamps, whereby to insure maximum intensity of illumination of said lamps upon adjustment of said dimmer to provide the same, said means comprising additional turns of the winding of said autotransformer dimmer connected between one side of said source and said lamps.

8. In an illumination control system, in combination, a group of electric lamps, a source of alternating current supply therefor, a variable autotransformer dimming device connected across said source for controlling the voltage of said lamps, regulating means for said dimming device comprising a plurality of sending impedances of the variable autotransformer type connected across said source, each of said impedances having an associated movable contact arm to provide for preselection of a definite value of control voltage, means associated with said sending impedances selectively to provide a balancing control circuit, said last mentioned means including a receiving impedance of the variable autotransformer type, means including a reversible electric motor operable automatically upon unbalancing of said control circuit to adjust said receiving impedance directly in accordance with and to a degree definitely corresponding to the preselected variation in value of said control voltage, as an incident to utilization of said sending impedances selectively, whereby said control circuit is balanced, and simultaneously to adjust said dimming device, whereby the voltage of said lamps is adjusted to and maintained at a value having a predetermined definite relationship to the preselected control voltage value, and means including an electromagnetically operable brake releasable automatically upon balancing of said control circuit to insure substantially immediate stopping of said motor after operation of the latter in either direction.

9. In an illumination control system, in combination, a group of electric lamps, a source of alternating current supply therefor, means for adjusting the voltage of said group of lamps to and maintaining the same substantially constant at a desired value, said means comprising a variable autotransformer dimming device connected across said source, regulating means for said device including an impedance of the variable autotransformer type for supplying a variable control voltage, means associated with said sending impedance to provide a balancing control circuit, said last mentioned means including a receiving impedance of the variable autotransformer type, means including a reversible electric motor operable automatically upon unbalancing of said control circuit, as an incident to adjustment of said sending impedance, to adjust said receiving impedance, whereby said control circuit is balanced, and simultaneously to adjust said dimming device, whereby the voltage of said lamps is adjusted to and maintained at a value having a predetermined definite relationship to the control voltage value, and means including an electromagnetically operable brake releasable automatically upon balancing of said control circuit to insure substantially immediate stopping of said motor after operation of the latter in either direction.
